Primary Examiner — Michelle E. Wilson(57) **CLAIM**

The ornamental design for a manual washing machine, as shown and described.

DESCRIPTION

FIG. 1 is a front elevation view of a manual washing machine;

FIG. 2 is a rear elevation view thereof;

FIG. 3 is a right side elevation view of the manual washing machine, a left side elevation view being a mirror image of the right side elevation view;

FIG. 4 is a top plan view of the manual washing machine;

FIG. 5 is a bottom plan view thereof;

FIG. 6 is a front, top, and right side perspective view thereof;

FIG. 7 is a rear, top, and right side perspective view thereof;

FIG. 8 is a front, bottom, and right side perspective view thereof; and,

FIG. 9 is a rear, bottom, and right side perspective view thereof.

The broken lines shown in the drawings represent portions of the manual washing machine and form no part of the claimed design.
